UNITED STATES PATENT OFFICE.

WORDEN I. SMITH, OF SILVERLAKE, INDIANA.

AUTOMOBILE-SIGNAL.

1,086,234.

Specification of Letters Patent.

Patented Feb. 3, 1914.

Application filed March 13, 1913. Serial No. 754,031.

To all whom it may concern:

Be it known that I, WORDEN IVEN SMITH, a citizen of the United States, residing at Silverlake, in the county of Kosciusko and State of Indiana, have invented certain new and useful Improvements in Automobile-Signals; and I do hereby declare the following to be a full, clear, and exact description of the invention, such as will enable others skilled in the art to which it appertains to make and use the same.

This invention relates to new and useful improvements in automobile signals, and has for its object to provide a device which will indicate the direction which the automobile is going to take.

Another object of my invention is to provide a device which will indicate the above both in the day time and after dark.

Still another object of my invention is to provide an indicator which will operate in combination with the tail lamp of a motor vehicle, so that it will be unnecessary to carry more than one light in the rear.

With the above and other objects in view, I will now proceed to describe my invention in the following specification and accompanying drawings, in which—

Figure 1 is a diagrammatical plan view of my invention as it would appear when in use. Fig. 2 is a longitudinal sectional view showing the particular arrangement of parts. Fig. 3 is a longitudinal sectional view taken on line 3—3 of Fig. 2. Fig. 4 is a side view of the revoluble cylinder; and Fig. 5 is a cross sectional view of one of the cylinders.

Referring to the drawings by characters of reference, 1 indicates generally one of my signals in position on the front of an automobile.

2 is the wire or flexible member by means of which the same is operated. One of the wires 2 is carried rearwardly from the front of the car to a pulley 3 which it is passed around on its way back to the controlling device, indicated generally at 4. A second flexible member 5 is attached to the operating mechanism 4 and extends rearwardly to the rear signal 6.

The operating mechanism consists essentially of the plate 7 which is attached to the foot board 8 of an automobile. A plunger 9 is provided at its upper end with a plate 10 upon which the operator presses when he

desires to indicate the direction which will be taken. The plunger 9 is provided adjacent its upper end with a recess 11, the use of which will be more fully hereinafter described. A second recess 12 is provided a short distance below the recess 11, the use of which will also be more fully described hereafter. The end of the plunger 9 opposite the plate 10 is provided with an aperture through which the pivot 13 is adapted to pass. This pivot 13 is connected to the bifurcated arm 14 of a bell crank. This bell crank is preferably pivoted as shown at 15 and supported by means of the downwardly extending projection 16 which is attached to the plate 7 by means of the flange 17, through which a rivet 18 is adapted to extend. The bell crank is provided with a downwardly extending arm 19 having at its lower end an aperture 20, in which the flexible member 8 is adapted to be fastened. The flexible member 5 is also attached to the arm 19 by means of the aperture 20 and it will be seen when the plunger 9 is pressed downwardly, the arm 19 will exert pull on each of the flexible members and cause the cylinders of the indicators to rotate.

The cylinder consists of a fixed cylinder 21 having at each end the closures 22. On one of these closures I preferably provide an elongated bearing 23, having an aperture extending transversely therethrough. A larger aperture extending at right angles through the elongated bearing is adapted to receive the end of the shaft 24, this shaft being bent at right angles as shown at 25, to form the U-shaped member 26. The arms 25 are adapted to receive the clamps 27 of the lamp socket 28 in which the lamp 29 is adapted to seat. The coil spring 30 is attached to the shaft 24 at 31, and is adapted to cause the inner rotary cylinder to return to its normal position.

The inner rotary cylinder is composed of the cylindrical member 32 having closures at each end thereof, one of said closures being provided with a spool upon which the end of either the flexible member 2 or 5 is adapted to wind. This spool is preferably composed of the drum 33 and the flange 34, which flange is adapted to keep the flexible member from slipping off of the end of the drum and becoming entangled in the shaft.

A switch comprising a base member 35 and a switch arm 36 is placed at a conven-

110

ient position on the body of the car. This switch is adapted to control the lamp circuit so that the lights may be either turned on or off as the operator desires.

- 5 The indicators 1 and 5 are each provided with supports 37 which are adapted to be attached to the ends of an automobile. The support used on the forward end consists preferably of an upstanding stud 38 around 10 which the sleeve 39 is adapted to be clamped. The cylinder 21 is attached to this sleeve 39 by means of rivets or bolts 40. The inner rotatable cylinder 32 is preferably provided with letters as shown at 41 which are 15 adapted to register with an opening 42 in the outer cylinder and allow the light to show through. The inner cylinder is also provided with a clear opening 43 which is adapted to register with the opening 42 for 20 the purpose described above. A stop 44 having a flange 45 is suitably mounted to the inner side of the fixed cylinder 21, this stop being adapted to prevent the inner cylinder from rotating beyond the desired 25 point.

In operation, should the operator desire to go to the right he will press the plunger 9 and cause the notch 12 to hook under the plate 7, and it will be seen that upon transmitting power to the bell crank arm 19 pull 30 will be exerted on the members 2 and 5 and the inner cylinder 32 will be rotated for a partial distance. Should the operator desire to go to the left the plunger 9 is pushed 35 down far enough so that the notch 11 will engage beyond the plate 7, and it will be seen that the inner cylinder 32 will rotate for substantially its entire distance and bring up the desired letters on its face. 40 Upon releasing the plunger 9 the spring 30 returns the cylinder to its normal position

and causes the plunger to rise, and the cylinder will indicate a clear road.

While in the foregoing I have shown and described a preferred embodiment of my invention, it is to be understood that I may change the structure and arrangement of parts without in any way departing from the spirit and scope of the claims. 45

Having thus fully described my invention, 50 what I claim is:

1. In a device of the character described, cylinders, a shaft extending longitudinally through said cylinders, the said shaft being substantially U-shaped intermediate its 55 length, a clamp fixed to the arms of the U-shaped section on the said shaft, an electric lamp socket held between the arms of the U-shaped section and the clamp, and means to control the lighting of a lamp when in 60 position in the socket.

2. In a device of the character described cylinders, a shaft extending longitudinally through said cylinders, said shaft being substantially U-shaped intermediate its length, 65 a clamp secured to the arms of the U-shaped member formed on the shaft, said clamp being enlarged intermediate its longitudinal extremity, an electric lamp socket secured in the enlarged portion of the clamp, electrical connections attached to the lamp socket, 70 a lamp adapted to be held in the socket and a switch to control the flow of current through the connection and thereby control the lighting of the lamp. 75

In testimony whereof I affix my signature in presence of two witnesses.

WORDEN I. SMITH.
